UNITED STATES PATENT OFFICE.

CHARLES A. KINNEY, OF SENECA, PENNSYLVANIA.

INTERNAL-COMBUSTION-ENGINE STARTER.

1,025,810.

Specification of Letters Patent.

Patented May 7, 1912.

Application filed June 2, 1911. Serial No. 630,763.

To all whom it may concern:

Be it known that I, CHARLES A. KINNEY, a citizen of the United States, and a resident of Seneca, in the county of Venango and State of Pennsylvania, have made certain new and useful Improvements in Internal-Combustion-Engine Starters, of which the following is a specification.

My invention relates to improvements in devices for starting internal combustion engines, and it consists in the combinations, constructions, and arrangements herein described and claimed.

An object of my invention is to provide means by which the shaft of the engine may be rotated without the necessity of the usual cranking operation.

A further object of my invention is to provide means for reversing the direction of rotation of the engine by the movement of a single lever.

A further object of my invention is to provide means whereby the rotation of a fly wheel on the main shaft may be caused 25 to impart its motion to the shaft itself by means of structures of a peculiar form.

Other objects and advantages will appear in the following specification and the novel features of the device will be particularly 30 pointed out in the appended claims.

My invention is illustrated in the accompanying drawings forming part of this application in which—

Figure 1 is a side view of the mechanism 35 for operating the clutch; Fig. 2 is a horizontal section through the fly wheel and clutch mechanism.

In the following description of the device, I shall set forth only those parts which are 40 new, and are necessary to an explanation of the working of the device. The device is applicable to internal engines of any type.

In carrying out my invention, I provide the main shaft S with a fly wheel F. The 45 fly wheel F is not secured to the shaft but revolves loosely thereon. On one side of the fly wheel is an annular groove or channel C having an outer frictional contact surface c and an inner frictional contact surface c'.

Pivoted secured at m on the frame member M is a yoke Y, while rotatably mounted in the yoke is a small stub shaft S' bearing a gear g arranged to mesh with a gear G, which is keyed to the shaft S. The end of 50 the stub shaft s' is provided with a friction wheel W, which is adapted to engage either

of the contact surfaces c or c' on the fly wheel. A rod r is secured to a lug l on the shaft S'. This rod r is connected to a rod r^x by means of spring connections r^y. The 60 rod r^x in turn is connected to a lever handle L. The lever handle L has three positions; one a neutral position shown in the figure; another position a which will impart a direct or forward movement to the engine, 65 and a position b which is the reverse position.

Secured to the lever L is a second lever L' which is connected by a link l^x with another link l^y. The latter is secured to a bell-crank lever K pivoted at k and connected by a link l^z to a rod r^w which operates the swinging link r^v pivotally connected at its bottom to the rod r^t which governs the magneto or fuel feed, not shown.

From the foregoing description of the various parts of the device, the operation thereof may be readily understood. The fly wheel F is started in any convenient manner and after a sufficient momentum is obtained the lever L may be manipulated to turn the engine in either direction. Thus if it is pushed forward to the position a, the friction wheel W will engage the inner friction surface c' of the fly wheel, thereby 80 turning the wheel W of the shaft S' and the gear g in the opposite direction from that in which the fly wheel is running. The gear g engages the gear G on the shaft, and therefore turns the shaft in the same direction in which the fly wheel is running.

When the lever L is reversed to the position b, then the friction member w is pulled against the contact surface c of the fly wheel F and therefore the wheel W, the shaft S', and the gear G, revolve in the same direction with the fly wheel, while the engagement of the gear G with the gear g drives the shaft in the reverse direction from that in which the fly wheel is rotating. When the lever L is at the position shown in Fig. 1, then the friction member w is free from the contact surface c', and the rotation of the fly wheel therefore will not affect any movement of the engine. At the same time that the lever 95 L is being shifted, the lever L' is shifted so as to cut off either the magneto circuit, or the fuel supply by means of the rod r^t.

Since the shifting of the lever L' is accomplished by merely grasping the latter with 100 the fingers, when manipulating the lever L, it is obvious that the fuel supply may be cut 105

off when the lever L is being shifted in either direction.

While I have shown the clutch in Fig. 2 as a friction clutch, it is obvious that the wheel W may be a gear, and that the engaging surfaces c and c' may be provided with rack teeth, without departing from the spirit or scope of the invention.

I claim:—

- 10 1. In a starting device for internal combustion engines, the combination with a main shaft, of a fly wheel loosely mounted thereon and being provided with an annular groove, and a clutch member for connecting the fly wheel with the shaft, said clutch member comprising a pivoted rotatable member arranged to contact with the inner or outer edges of said groove, means for transmitting motion from the pivotal contact member to the main shaft, and means for shifting said pivotal contact member.

20 2. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for transmitting the rotary motion of said stub shaft to said main shaft, and means for moving said yoke to bring said rotatable member into engagement with either the inner or the outer edges of said groove.

30 3. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for moving said yoke to bring said rotatable member into engagement with either the inner or the outer edges of said groove.

40 4. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for moving said yoke to bring said rotatable member into engagement with either the inner or the outer edges of said groove, and means for imparting the movement of said stub shaft to said main shaft.

50 5. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for imparting the rotary motion of said stub shaft to said main shaft, means for moving said yoke to bring said rotatable member into engagement with either the inner or the outer edges of said groove, said means comprising a pivoted lever, and a rod connecting a portion of said lever with said stub shaft.

60 6. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, intermeshing gears on said stub shaft and said main shaft, means for moving said yoke to bring said rotatable member into engagement with either the inner or the outer edges of said groove, said means comprising a pivoted lever, and a rod connecting a portion of said lever with said stub shaft.

70 7. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for imparting the rotary motion of said stub shaft to said main shaft, means for moving said yoke to bring said rotatable member into engagement with either the inner or the outer edges of said groove, said means comprising a pivoted lever, and a rod connecting a portion of said lever with said stub shaft.

80 8. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for imparting the rotary motion of said stub shaft to said main shaft, means for moving said yoke to bring said rotatable member into engagement with either the inner or the outer edges of said groove, said means comprising a pivoted lever, and a rod connecting a portion of said lever with said stub shaft.

90 9. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, intermeshing gears on said stub shaft and said main shaft, means for moving said yoke to bring said rotatable member into engagement with either the inner or the outer edges of said groove, said means comprising a pivoted lever, and a rod connecting a portion of said lever with said stub shaft.

100 10. In a starting device for internal combustion engines, a main shaft, a fly wheel loosely disposed on said main shaft, said fly wheel being provided with an annular groove, a frame member, a yoke pivotally secured to said frame member at one end, a stub shaft rotatably carried by said yoke and being provided with a rotatable member on the end thereof normally disposed within the groove in said fly wheel, means for imparting the rotary motion of said stub shaft to said main shaft, means for moving said yoke to bring said rotatable member into engagement with either the inner or the outer edges of said groove, said means comprising a pivoted lever, and a rod connecting a portion of said lever with said stub shaft.
